DESIGN FOR A JEWELRY COMPONENT

Benjamin Patek, Bronx, N. Y.

Application May 22, 1948, Serial No. 146,542

Term of patent 3½ years

(Cl. D45—1)

To all whom it may concern:

Be it known that I, Benjamin Patek, a citizen of the United States, residing at 2820 Morris Avenue, in the county of the Bronx, and State of New York, have invented a new, original, and ornamental Design for a Jewelry Component, of which the following is a specification, reference being had to the accompanying drawing, forming part thereof.

Figure 1 is a top plan view of a jewelry component, showing my new design, and Figure 2 is a side elevational view thereof.

I claim:

The ornamental design for a jewelry component, as shown.

BENJAMIN PATEK.
